UNITED STATES PATENT OFFICE

2,577,174

ELECTRIC LIGHT FIXTURE HAVING A CLUSTER OF LIGHT SOCKETS MOUNTED THEREON

Joseph Worth, New York, N. Y., assignor, by mesne assignments, to Leviton Manufacturing Company, Brooklyn, N. Y.

Application October 25, 1947, Serial No. 782,181

4 Claims. (Cl. 240—78)

1

This invention relates to an electric lighting fixture. More particularly, it is concerned with a fixture having a cluster of light sockets mounted thereon.

An object of this invention is to provide in a device of the character described, a single integral bracket adapted to have mounted thereon a plurality of interconnected electric light sockets, whereby electric bulbs mounted in the sockets extend in such directions as to avoid undue heating of the wiring connections on one socket by the bulb in an adjacent socket.

Another object of this invention is to provide in a device of the character described, a single bracket provided with spaced integral members for mounting a plurality of electric light sockets, said sockets being so arranged and interconnected as to reduce the amount of necessary splicing to a minimum.

A further object of this invention is to provide in a device of the character described, including a glass bowl, a single mounting bracket for a plurality of electric bulb sockets, said bracket being in the form of a polygonal member of minimum dimensions thereby reducing the shadow effect of said bracket with respect to said glass bowl.

Still another object of this invention is to provide in a device of the character described, a mounting bracket for a plurality of electric light bulbs so arranged that the wiring interconnecting the sockets is disposed entirely at the base of said sockets and the sockets being so arranged that the wiring on one socket is remote from the heat generated by a bulb mounted in an adjacent socket.

Still a further object of this invention is to provide in a device of the character described, a unitary mounting bracket for a plurality of electric light sockets, said bracket comprising a base of polygonal shape having socket supporting wing members angularly related to said base and provided with notched portions between said base and said wing members to facilitate the passage of wiring interconnecting the said sockets.

Yet a further object of this invention is to provide in a device of the character described, a mounting bracket for a plurality of electric bulb sockets, said bracket comprising a substantially triangular shaped base member having wing portions extending from the apices thereof, and providing means for securing the sockets at right angles thereto, said wing portions being adapted to be bent so that the sockets mounted thereon may be disposed at various angles relative to said base member.

2

Another object of this invention is to provide a rugged electric lighting fixture which shall be relatively inexpensive to manufacture, easy to install, is readily adjustable and which shall be practical and efficient to a high degree in use.

Other objects of this invention will in part be obvious and in part hereinafter pointed out.

The invention accordingly consists in the features of construction, combination of elements and procedural details which will be exemplified in the method and construction hereinafter described, and of which the scope of application will be indicated in the following claims.

In the accompanying drawing, in which is shown various possible illustrative embodiments of this invention,

Fig. 1 is a side elevational view of an electrical fixture embodying the invention, with parts thereof in section;

Fig. 2 is a view taken on the line 2—2 of Fig. 1, with parts in section;

Fig. 3 is a view taken on the line 3—3 of Fig. 1;

Fig. 4 is a perspective view of the bracket embodying the invention;

Fig. 5 is a side elevational view of the bracket fixed on a support with parts in section and parts broken away;

Fig. 6 is a bottom plan view of a socket used with the fixture shown in Fig. 1; and

Fig. 7 is a diagrammatic view of the circuit connections for the sockets shown in Fig. 2.

Referring now in detail to drawing, 10 designates the electrical lighting fixture embodying the invention. The same comprises a reflecting bowl 11 formed with a central opening 12. The bowl 11 is supported on a threaded nipple 13 by being clamped between a flanged member 14 and a flanged washer 15 which are mounted on the nipple 13.

40 The member 14 comprises a wall 16 which lies in contact with the outer surface of bowl 11. The member 14 is formed with an upwardly extending axial flanged collar 17 which extends upward, through the opening 12 in the bowl 11.

45 The washer 15 comprises a wall 18 formed with an axial opening 19 and with an annular skirt portion 20 which extends downwardly into contact with the inner surface of the bowl 11.

An ornamental cap nut 21 is screwed on the 50 end of nipple 13 with the inner portion thereof bearing against the member 14 at the base of the collar 17 thereof. The washer 15 is clamped against the inner surface of the bowl 11 by means of a nut 22 on the nipple 13.

55 A bracket member 25 is mounted on the threaded nipple 13, being disposed above the nut

22 and in spaced relation thereto. The bracket 25 comprises a substantially triangular shaped bottom wall 26. The wall 26 comprises angularly related sides 27, 28, 29. Extending from the wall 26 at right angles thereto and disposed between the sides 27, 28, 29, are bent extensions which form similar wings 30, 31, 32. The bend line 30a which forms a junction between the wing 30 and the wall 26 interconnects sides 27 and 28; the bend line 31a interconnects sides 28 and 29; and the bend line 32a interconnects sides 29 and 27. The wing 30 comprises an inclined edge 33 extending upwardly and outwardly from side 28. From the edge 33 there extends a horizontal top edge 34. A vertical edge 35 extends downwardly from edge 34 and a horizontal edge 36 parallel to edge 34 extends inwardly from edge 35. A curved edge 37 interconnects bottom edge 36 and side 27. The edge 36 is disposed above the plane of the bottom wall 26. The edges 33 and 27 form a notch as shown in Fig. 4 for the purpose hereinafter appearing. The wing 30 forms an acute angle with respect to the edge 27. Wings 31 and 32 are similar to wing 30 and are likewise connected to the wall 26. It will be apparent from a consideration of Fig. 3 that the wings 30, 31, 32 are equiangularly disposed to each other, and furthermore, are disposed tangentially of a common circle having a centre coinciding with the centre of bottom wall 26.

Furthermore, the edge 35 on the wing 30 projects outwardly and beyond the corners formed by the intersection of the side 27 and the bend line 32a. Each of the wings 30, 31 and 32 is formed with a threaded opening 38 adjacent the edge 35 for the purpose hereinafter appearing. The base 26 is formed with a central through opening 40 which will admit the passage of nipple 13.

In mounting the bracket 25 on the nipple 13, a nut 41 is screwed onto the nipple 13 above nut 22 and in spaced relation thereto. The bracket 25 is positioned on the nipple 13 with the bottom face of wall 26 abutting the nut 41. A hickey 42 is screwed onto the nipple 13 immediately above the bracket 25 and in contact therewith. The hickey 42 comprises a pair of spaced, aligned circular walls 43, 44 interconnected by an inclined arm 45. The lower wall 43 is of slightly larger diameter than the upper wall 44. The walls 43, 44 are formed with aligned, threaded central openings 43a, 44a, respectively. The threaded opening 43a of wall 43 receives the upper end of nipple 13. The bracket 25 is thus clamped between the nuts 41 and the hickey 42, thereby fixing the bracket on the nipple 13. A threaded tubular fixture supporting member 13a is aligned with the nipple 13. The lower end of the member 13a is screwed into opening 44a of the wall 44 of the hickey 42. A nut 13b on the member 13a locks the member to the hickey.

Mounted on each of the wings 30, 31, 32 at right angles thereto is an electric bulb socket 50. The bulb socket 50 comprises a tubular shell 51 of insulating material which is closed at one end by a base wall 52 having an inner face 53 and an outer face 54. The usual tubular metallic receptor contact member 55, which is formed with a spiral groove 56, to receive the base of a bulb, not shown, is mounted within the shell 51. A pair of oppositely disposed extensions 57, 57a of member 55, extending at right angles to the wall of the member, are disposed in contact with the inner face 53 of the base 52. The extensions 57, 57a have conducting eyelets 58, 58a

secured thereto which extend through the base wall 52 to the back face 54. A spring contact 59 is mounted on the center of the inner face 53 of the base wall 52 being disposed between the extensions 55. An eyelet 60 secures the contact 59 to the base wall and extends through the wall to the back face 54. The base 52 is formed on its rear face 54 with a raised recessed diametrical portion 61 which encloses the aligned rear ends 10 of eyelets 58, 58a and 60. The rear face 54 is furthermore formed with diametrically opposed recesses 62, 62a disposed at right angles to raised portion 61. The recesses 62, 62a are formed with transverse through openings 63. The openings 15 63 terminate in recesses 64 of enlarged diameter, on the face 53 of the base 52.

Each of the sockets 50 is mounted on one of the wings 30, 31, 32 of the bracket 25, the end portion of the wing being received in recess 62 or 62a on the back face 54 of the socket thereby preventing the socket from being turned on its axis. A headed screw 65 passing through the opening 63 in the wall 52, is screwed into the threaded opening 38 in the wing with the head 25 of the screw being received in the recess 64 in the base 52. It will be apparent from a consideration of Fig. 2, that each of the sockets 50 extends at right angles to the wing on which it is mounted. Furthermore, the length of the wing 30 is such that the wall 51 of the socket is disposed close to inclined edge 33 of the adjacent wing. The inclined edge 33 permits the sockets 50 to be mounted closely adjacent the centre of the bottom wall 26 of the bracket.

35 The sockets 50 are wired together in parallel, in accordance with the diagrammatic circuit shown in Fig. 7.

The receptor members 55 are interconnected through the eyelets 58, 58a by wires 70, 71 and a single terminal lead wire 72 extends from one of the members 55. Similarly, spring contacts 59 are interconnected through the eyelets 60 by wires 73, 74, 75 with a single terminal lead 76 extending from one of the eyelets 60. The leads 72, 76 are thus available for interconnection to the positive and negative sides of current carrying lines.

It will be noted from a consideration of Fig. 2, that the wires 70, 71, 72, 73, 74, 75 and 76 may 50 be readily inserted between the bottom edge 36 of the wings and the adjacent edges 27, 28, 29 of the base wall 26. This reduces the length of the connecting wires to a minimum and makes their terminal ends readily available for soldering to the appropriate eyelets on the sockets 50. The other ends of the lead wires 72, 76 are readily inserted into the lower end of the member 13a and pass upwardly therethrough for interconnection to power lines.

60 The sockets 50 are arranged in tandem and are disposed at an angle of 120° to each other. When the bulbs are screwed into the sockets, the outer, hot portions of the bulb are remote 65 from wiring connections of the adjacent sockets thereby reducing the possibility of deterioration of the insulation on the sockets connection.

The wings 30, 31, 32 may be readily bent along the bend lines 30a, 31a, 32a respectively, towards or away from the bottom wall 26. This 70 permits adjustment of the sockets 50 relative to the axis of the nipple 13 and is particularly advantageous in cases where the curvature of the bowl 11 is such that the end of the bulbs in the sockets might contact the inner surface of the bowl. In this case, the wing would be bent out-

wardly, thereby inclining the sockets 50 upwardly.

It will thus be seen that there is provided a device in which the several objects of this invention are achieved, and which is well adapted to meet the conditions of practical use.

As various possible embodiments might be made of the above invention, and as various changes might be made in the embodiment above set forth, it is understood that all matter herein set forth or shown in the accompanying drawing is to be interpreted as illustrative and not in a limiting sense.

Having thus described my invention, I claim as new and desire to secure by Letters Patent:

1. A lighting fixture comprising a cluster bracket, said bracket comprising a base, wing members extending upwardly from the base substantially at right angles thereto, and being equiangularly spaced apart, said wing members being tangent to a common cylinder and extending beyond the base to the same side of a radial line from each wing to the axis of the base, and electric bulb receiving sockets fixed to the extending portions of said wing members, the axes of said sockets being disposed in a common plane, the axis of each socket being disposed at right angles to the wing member on which it is mounted, and each socket being disposed beyond the wing member adjacent to the wing member on which the socket is mounted.

2. A lighting fixture comprising a bracket having a bottom wall, and a plurality of integral wings extending upwardly from said wall substantially at right angles thereto and disposed tangentially of a common circle and having end portions projecting beyond said bottom wall, said bottom wall having edges forming a polygon, and said wings extending from portions of said bottom wall between said edges, and lying in planes forming acute angles with said edges, and electric bulb sockets attached to the projecting portions of said wings, the axes of said sockets being in a common plane and forming a polygon.

3. A lighting fixture comprising a bracket having a bottom wall, and a plurality of integral

wings extending upwardly from said wall substantially at right angles thereto and disposed tangentially of a common circle and having end portions projecting beyond said bottom wall, said bottom wall having edges forming a polygon, and said wings extending from portions of said bottom wall between said edges, and lying in planes forming acute angles with said edges, the lower edges of said end portions of said wings being spaced above the plane of said bottom wall, sockets attached to said end portions, said sockets extending at right angles to said wings, the axes of said sockets being in a common plane and forming a polygon.

4. A lighting fixture comprising a bracket having a bottom wall, and a plurality of integral wings extending upwardly from said wall substantially at right angles thereto and disposed tangentially of a common circle and having end portions projecting beyond said bottom wall, said bottom wall having edges forming a polygon, and said wings extending from portions of said bottom wall between said edges, and lying in planes forming acute angles with said edges, the lower edges of said end portions of said wings being spaced above the plane of said bottom wall, sockets attached to said end portions, said sockets extending at right angles to said wings, and wiring connecting said sockets in parallel and passing through the notches formed between said end portions of said wings and their respectively adjacent edges of said bottom wall.

JOSEPH WORTH.
